OUTLET BOX SUPPORT

Harold Kuykendall, Lancaster, Pa.

Application June 10, 1940, Serial No. 339,809

2 Claims. (Cl. 248—201)

The present invention relates to new and useful improvements in supports for electrical outlet boxes and has for its primary object to provide, in a manner as hereinafter set forth, novel means whereby a box of this character may be expeditiously mounted and adjusted to any desired position between a pair of studs, joists or other supports.

Another very important object of the invention is to provide a support of the character described comprising unique means for securing the edges of plaster board, wire lath, etc., adjacent the outlet box.

Other objects of the invention are to provide a support of the aforementioned character which will be comparatively simple in construction, strong, durable, highly efficient and reliable in use, compact, light in weight and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation, showing an electrical outlet box mounted on a supporting structure in accordance with the present invention.

Figure 2 is a top plan view thereof.

Figure 3 is a view in vertical section through the outlet box and the supporting bars, taken substantially on the line 3—3 of Fig. 1.

Figure 4 is a perspective view of one of the bars.

Figure 5 is a perspective view of an intermediate portion of one of the bars, showing one end portion of a plaster board or wire lath holder engaged therein.

Figure 6 is a perspective view of one of the plaster board or wire lath holders.

Figure 7 is a perspective view of one of the outlet box lugs.

Figure 8 is a perspective view, showing a modified form of bar.

Referring now to the drawings in detail, it will be seen that the reference numeral 1 designates a pair of bars of suitable metal, said bars being substantially S-shaped in cross section thus providing longitudinal channels 2. The end portions of the bars 1 have formed therein longitudinally spaced holes 3 which accommodate nails 4 for securing said bars in position between a pair of studs, as at 5. It will be observed that

the bars 1 are mounted in spaced, opposed parallelism to each other.

Mounted vertically between the bars 1 is a pair of holders which are designated generally by the reference numeral 6, said holders also being of any suitable metal. It may be well to here state that the holders 6 are adapted to secure sheets of plaster board, wire lath or other wall coverings in position. In Fig. 1 of the drawings, portions of plaster boards have been illustrated, as at 7.

Each holder 6 comprises a bar 8 the end portions of which are engageable and adjustable in one of the channels 2 of the bars 1. The bars 1 are reversible thus permitting either of the channels 2 to be used. The holders 6 further include angular flanges 9 which extend closely adjacent the sides of the outlet box, as at 10, for engagement with the front or outer faces of the plaster boards 7 for firmly retaining said plaster boards. The ends of the bars 8 of the holders 6 project beyond the angular flanges 9 for engagement in the channels 2.

It is thought that the manner in which the support functions will be readily apparent from a consideration of the foregoing, particularly to those skilled in the art to which the invention pertains. Briefly, the lugs 11 of the outlet box 10 are engaged in the opposed channels 2 of the bars 1 and said outlet box is slidably adjusted to the desired position between the studs 5. The end portions of the bars 8 of the holders 6 are then inserted in the opposed channels 2 of the bars 1 and said holders are engaged with the sides

30 of the outlet box 10. The bars 1 are then crimped in a manner to provide shoulders or abutments 12 at the end portions of the bars 8 for securing the assembly in position. The plaster board 7 may then be applied, said plaster board being conveniently engaged in the holders 6. It will be observed that the opening in the wall which accommodates the outlet box 10 is bordered by the bars 1 and the holders 6.

In the modification illustrated in Fig. 8 of the drawings, the reference numeral 13 designates a metallic bar of substantially U-shaped cross section provided with an inturned flange 14. Thus, the bar 13 is provided with a single channel 15 for the reception of the outlet box lugs 11 and the end portions of the holder bars 8. The flange 14 coats with the front of the bar 13 for frictionally clamping the members 11 and 8 in position in the channel 15. Spaced holes 16 are provided in the end portions of the bar 13 for securing same to the studding 5.

It is believed that the many advantages of an outlet box support and plaster board, etc., holder constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A support of the class described comprising a pair of spaced, parallel bars adapted to be mounted between a pair of supports, said bars having opposed channels therein for the reception of lugs on an electrical outlet box, and holders for a wall covering mounted between the bars, said holders comprising bars having their end portions engaged in the channels, said holders

further including angular flanges on the second named bars engageable with the wall covering.

2. A support of the class described comprising a pair of spaced, parallel bars of substantially S-shaped cross section adapted to be mounted between a pair of supports, said bars having channels therein adapted to be brought selectively into position for use, said channels for the reception of lugs on an electrical outlet box for mounting said box between the bars, and holders for a wall covering mounted between the bars, said holders including bars having their end portions engaged in certain of the channels, and angular flanges on the second named bars engageable with the wall covering for retaining same.

HAROLD KUYKENDALL.
